JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA.

LIGHTNING ARRESTER.

Application filed February 11, 1922. Serial No. 535,810.

To all whom it may concern:

Be it known that I, JOSEPH SLEPIAN, a citizen of the United States, and a resident of Swissvale, in the county of Allegheny and State of Pennsylvania, have invented a new and useful Improvement in Lightning Arresters, of which the following is a specification.

This invention relates to lightning arresters, more particularly to a simple form of lightning arrester of the spark gap type having properties superior to those of prior lightning arresters.

Up to the present time, lightning arresters were generally of two types; first, spark gap and second, chemical. Spark gap lightning arresters generally consisted of cylinders, plates or disks of material, such as brass, graphite, and the like separated by air spaces and insulated from each other. In some cases the air gaps were shunted by resistors, and in some instances instead of air gaps a dielectric, such as mica, was placed between the disks. These various types of lightning arresters had many disadvantages, it being difficult to obtain structures which operated successfully under all conditions.

There has also been proposed a lightning arrester consisting essentially of alternate blocks of film-forming metal and graphite or other material which did not fuse to the metal. Spacers of sheet mica were placed between the blocks. Generally the metal used was aluminum, thereby providing an oxidizable metal which formed a non-conducting coating on the surface thereof which was intended to be ruptured upon the passage of an abnormal voltage after which oxidation of the metal healed the rupture. The action of this arrester is chemical.

Unlike the chemical arresters, the spark-gap arresters do not merely discharge the abnormal voltage on a power line, but when they function they also constitute a short-circuit or low resistance path for the normal or dynamic voltage of the power line. The non-arching properties of the gap electrodes is depended upon for clearing this short circuit at the end of the half cycle. On

systems of large capacity, however, so much power is expended in this short circuit that the gaps are unable to clear, and in order to prevent destruction of the arrester, it is necessary to put limiting resistance in series. This, however, also limits the ability to discharge the abnormal voltage so that the protective power is impaired.

The electrolytic lightning arrester, which was the most widely used of the chemical arresters, consisted generally of plates or cups of aluminum or similar metal placed within each other, the spaces therebetween being filled with an electrolyte, such as a borax solution. The entire structure was generally immersed in a vessel filled with an insulating oil. The action of the arrester was dependent primarily upon the thin film of aluminum oxide on the plate which was broken down by the abnormal voltage of a lightning discharge.

This arrester had many desirable properties, being admirably fitted for use as a lightning arrester, but was subject to the disadvantage of the necessity of constant maintenance thereof. The film of oxide on the aluminum was very thin and deteriorated during the period when the arrester was inactive, and required periodical reforming or "charging" to restore the same. Since lightning arresters are placed on the line at various points which are more or less inaccessible, the necessity for periodically charging the electrolytic arrester became a source of considerable expense and trouble.

It is generally agreed that the value of the electrolytic arrester lay in its volt-ampere characteristic. Below a certain critical voltage, V_1 , the arrester had a high resistance and passed little current. For voltages above the critical voltage the arrester passed current freely, the current being calculated approximately by the equation

$$I = \frac{V - V_1}{R}$$

where R is a constant called the discharge resistance of the arrester, V , the voltage on

the arrester during discharge, and V_1 , the critical voltage at which current begins to flow through the arrester.

My new lightning arrester embodies the 5 desirable phenomena occurring in electrolytic lightning arresters, it being among the objects of the present invention to devise a lightning arrester which shall have the characteristic operating advantages and 10 efficiency of the electrolytic lightning arrester and obviate the disadvantage thereof of high maintenance cost.

It is a further object of the present invention to provide such a lightning arrester 15 which shall be simple in construction, be capable of manufacture in large quantities at a relatively low cost, which shall not require the services of expert workmen and which shall be efficient in operation.

20 I have discovered that a volt-ampere characteristic similar to that of the electrolytic arrester may be obtained by utilizing small air gaps between electrodes of material having a relatively high specific resistance. 25 This causes the current density in the discharge to be kept relatively small, usually a few amperes per square centimeter, so that no local heating occurs. The voltage of the discharge is relatively large, making the 30 discharge voltage of the same order as the break-down voltage of the gap. Such a condition is practically possible at atmospheric pressure only with minute gaps and I obtain a device capable of passing large 35 currents by providing a sufficiently large area in the electrodes forming the gaps.

In practising my invention, I provide 40 layers or bodies of a suitable material having a relatively high specific resistance, generally in the form of disks which may 45 consists of any suitable material. A composition which I have found to be effective in carrying out my invention consists of a mixture of carborundum, lampblack and kaolin which has been compressed and then 50 baked in the form of a rod which is then cut to form disks. The specific resistance of the material is about 100 ohms per centimeter cube. The faces of the disks are 55 made as smooth as possible and are treated with a very thin coat of plaster of Paris to prevent small particles of the resistance material from becoming loose.

55 The disks are assembled, being actually in contact at only a few points and being, over the major portion of the contacting surfaces, separated by minute gaps. With ordinary workmanship, the gaps will vary from fractions of a mil to several mils. 60 No portion of a gap should exceed about 8 mils, as then that portion becomes less effective in carrying discharge.

When a low voltage is applied, current is carried only at the few contact points and

since the resistance of the material is relatively high, only a small current is carried below the break-down voltage. When, however, the critical voltage is exceeded, the large number of minute gaps over the 65 faces of the disks break down and carry 70 current freely and practically uniformly over the entire surfaces thereof.

In the accompanying drawings forming 75 a part hereof, in which like reference characters indicate similar parts,

Fig. 1 is a view, partially in cross-section, of a lightning arrester made in accordance 75 with the present invention;

Fig. 2 is an enlarged view of two of the 80 bodies forming a section of my lightning arrester, the contact surfaces of said bodies and the gaps therebetween being exaggerated for the sake of clearness and illustrating the passage of current therethrough under low voltage;

Fig. 3 is a similar view showing the 85 passage of current through the bodies at a voltage above the critical or break-down voltage of the arrester;

Fig. 4 is a curve showing the relation 90 between the break-down voltage of a gap and the length thereof;

Fig. 5 is a curve showing the character 95 of discharge of a gap under different conditions of voltage and current, and

Fig. 6 is a view showing the various 95 phenomena in a glow discharge between two electrodes.

Referring particularly to Fig. 1, to any 100 point in a line 1 is connected a conductor 2 having a spark gap 3 of any suitable type in series therewith and connected to a lightning arrester 4. The lightning arrester comprises a tubular casing 5 of porcelain or other insulating material having an inwardly projecting annular flange 6 at the bottom thereof. A metal plate 7 having a conductor 8 secured thereto, connected to ground 9, is placed on flange 6.

Disks 10 of material having a high specific 110 resistance are placed on metal plate 7, a suitable number being assembled to provide an arrester having the desired break-down voltage. A metal plate 11 is placed on the uppermost disk 10 and a conductor 12 secured thereto is connected to conductor 2.

115 A cover member 13 generally of insulating material having an opening therein to allow the conductor 12 to pass therethrough is secured to the top of casing 5 and a 120 spring 14, interposed between metal plate 11 and cover 13, holds the disks 10 in fixed relation to each other. Disks 10 are ground smooth but nevertheless show minute elevations and depressions so that, when assembled, the disks touch at a relatively few 125 points 16 forming gaps 17 of relatively large area, as shown in Fig. 2. When the

voltage on the disks is low, the leakage current can pass between disks only at the points of contact 16, which are few in number and small in area. Therefore, the resistance of the arrester to the passage of current at a low voltage is very high and no appreciable current will pass under such conditions.

However, as illustrated in Fig. 3, when 10 break-down occurs at one or more points between the disks 10 owing to an abnormal voltage being applied thereto, the break-down extends over the entire surface of the disks, allowing current to pass therethrough 15 practically uniformly over the entire surface of the arrester. The current density at any point is kept small because the resistance of the disks opposes any concentration of the discharge and, therefore, no 20 local heating occurs, thus preventing the changing of the discharge from a form called the "glow discharge" which requires high voltage to sustain it to the form called the "arc", which requires only a low voltage 25 to be maintained.

As illustrated in Fig. 4, the break-down voltage for small gaps for most electrode materials, is a minimum when the length of gap is about .001 centimeters, being equal 30 to about $\frac{1}{3}$ mil. Therefore, the gap necessary for break-down should be about $\frac{1}{3}$ mil and, after break-down has occurred at such points between the disks, this discharge will pass to points having a greater separation. In practice, with the materials used, 35 I find that about 8 mils is the maximum effective separation which can be used practically, still maintaining a glow discharge.

Since the successful operation of my new 40 arrester depends on keeping the discharge in the form of a glow, and preventing the formation of an arc, it is well to consider the conditions under which glow discharge takes place. Fig. 5 shows the volt-ampere 45 characteristic of a gap for small currents. It will be seen for very small currents for which there is little heating of the cathode, the glow discharge takes place, and requires in excess of 350 volts to be maintained. 50 Upon the electrodes heating, the discharge changes abruptly from the glow to the arc, which requires a relatively small voltage, usually under 50 volts, to maintain.

It is my purpose in this invention to avoid 55 the formation of an arc after break-down because if an arc were formed, the voltage necessary to maintain the same would be relatively small, therefore resulting in the normal line voltage being capable of maintaining 60 the arc. By causing the discharge to be distributed over the entire surface of the disks, I avoid heating thereof and am, therefore, enabled to keep the glow discharge at all times. This distribution of the current

is effected by using electrodes of relatively 65 high specific resistance, for evidently then any tendency on the part of the discharge to concentrate is opposed by the ohmic resistance of the small section path offered to the discharge if it should concentrate. 70

To explain further why small gaps are desirable if concentration of discharge is to be prevented, it is necessary to consider the voltage-current density characteristics of the various parts making up a glow discharge. 75 Fig. 6 shows the structure of a glow discharge considerably magnified. At the electrode 18, which is the cathode, there is produced a very short dark space 20, known as the cathode dark space, corresponding in length to the minimum break-down gap shown in Fig. 4. Next to this is the cathode glow 21 also being of relatively small length, about four or five mils. Then comes the Faraday dark space 22 and the positive column 23 of considerably greater length. 80 85

A large part of the voltage necessary to maintain the glow is concentrated at and around the cathode dark space 20, which voltage, upon increase of current density, 90 tends to rise, that is, the voltage-current density curve is a rising one. The rest of the voltage is consumed in the positive column 23, which increases or decreases in length as the electrodes are separated or caused to approach each other. 95

The voltage in the positive column varies in an inverse manner with the current density so that the voltage-current density curve is a falling one. It is evident that a 100 form of discharge with a falling voltage-current density characteristic tends to concentrate in section, because in so doing the voltage for a given current is lowered. As it is my purpose to reduce all effects which 105 tend to concentrate the discharge, I make the positive column as short as possible by as close a spacing of the electrodes as is practicable. It will be seen, therefore, that by the use of a small gap and electrodes of 110 considerable specific resistance, the discharge is kept in the glow form requiring several hundred volts for its maintenance. Such a discharge may be initiated at about the same voltage necessary to maintain the glow discharge. 115

In my new type of arrester, with ordinary workmanship, the distance between adjacent faces of disks will vary from zero at actual contacts to a mil or so at the points of greatest separation. There will always be, therefore, portions of the opposing disk faces which will be separated by the distance corresponding to the minimum sparking potential. Hence, the break-down potential of 120 the gaps between the disks will always be the minimum sparking potential for air, and 125 this is also nearly equal to the voltage re-

quired to maintain a short glow discharge.

The volt-ampere characteristic for a discharge across a gap having the minimum sparkover potential and with electrodes maintained cool is then as follows: Until the break-down potential, which is also the voltage necessary to sustain a glow discharge, is reached, no current passes. Large currents pass for voltages only slightly above the break-down potential. This is a characteristic similar to that of the aluminum electrolytic arrester.

I am aware that it has been proposed to construct a lightning arrester of two plates of high resistance material spaced apart with an air gap therebetween. In order to carry out this idea with usual air gaps, the material used would necessarily have a very high specific resistance to overcome the concentrating tendency of the long positive column. The specific resistance of the materials utilized must be so high that the discharge capacity of the arrester is seriously limited. If insufficiently high resistance material is utilized, the concentration of current and voltage at some point or points of the plates burns and punctures the material rendering it useless. Furthermore, the equality between voltage necessary to initiate the discharge and that necessary to sustain the same is lost unless the resistance is made so high as to keep the current density at an excessively low value.

Although, superficially, my new lightning arrester bears some resemblance to the carbon pile resistor, it differs therefrom in several material respects. I utilize high resistance material whereas the pile resistor is made of low resistance material. In my device, the pressure on the plates is kept constant whereas in the pile resistor the pressure is varied. My arrester operates by sparking at the gaps while in the pile resistor sparking is avoided. Further, there is no analogy between a lightning arrester and a carbon pile resistor which operate on entirely different principles and for different purposes.

It will be apparent from the above description of my invention that I have provided a lightning arrester which is extremely simple in construction and reliable in operation. The maintenance cost of the arrester is very low, as is the cost of production.

Although I have described my invention, giving a specific example of the construction thereof, it is obvious that various changes may be made in details of my invention without departing from the scope and spirit thereof. For instance, although I prefer to use gaps between adjacent disks as small as practical, it is apparent that various sizes of gaps may be utilized, and, although I

have mentioned 8 mils as the largest gap which is practical with the materials thus far used, this figure is not limiting but is merely illustrative of the gap lengths which I may use.

The resistance material stated in my specification has a specific resistance of about 100 ohms per centimeter cube but I may use material having a lower resistance, say about 25 ohms per centimeter cube provided that the heat conductivity thereof is sufficient to prevent local heating of the surfaces, and, therefore, prevent the formation of an arc.

I may use metals in place of non-metallic materials, it being merely necessary that the metal or other material have a high heat conductivity and a sufficient specific resistance to prevent the formation of an arc and so that the counter electromotive force developed under abnormal voltage is not less than the voltage necessary to maintain a glow discharge.

I claim as my invention:

1. A lightning arrester comprising a plurality of plates of high resistance material disposed in contact with each other.

2. A lightning arrester comprising a plurality of plane bodies of high resistance material disposed in contact with each other.

3. A lightning arrester comprising a plurality of plates of non-metallic conducting material disposed in contact with each other.

4. A lightning arrester comprising a plurality of plates of high resistance material disposed in contact with each other at a relatively small number of points.

5. A lightning arrester comprising a plurality of plates of high resistance material disposed in contact with each other at a relatively small number of points and being separated by small gaps at the remainder of the contact surfaces.

6. A lightning arrester comprising a plurality of bodies of high resistance material disposed in contact with each other at a relatively small number of points and being separated by small gaps at the remainder of the contact surfaces, the voltage necessary to break down said gaps being less than 500 volts per gap.

7. A lightning arrester comprising a plurality of bodies of high resistance material disposed in contact with each other at a relatively small number of points and being separated by small gaps at the remainder of the contact surfaces, the voltage necessary to break down said gaps being approximately 350 volts per gap.

8. A lightning arrester comprising a plurality of bodies of high resistance material disposed in contact with each other at a relatively small number of points and being separated by small gaps at the remainder

- of the contact surfaces, said gaps being less than 8 mils in length.
9. A lightning arrester comprising a plurality of bodies of high resistance material disposed in contact with each other at a relatively small number of points and being separated by small gaps at the remainder of the contact surfaces, said gaps varying from 0 to 5 mils in length.
- 10 10. A lightning arrester comprising a plurality of bodies of high resistance material disposed in contact with each other at a relatively small number of points and being separated by small gaps at the remainder of 15 the contact surfaces, the gas pressure in said gaps being substantially atmospheric.
11. A lightning arrester comprising a plurality of plates of high resistance material disposed in contact with each other, said 20 bodies being maintained at a relatively low temperature during a discharge.
12. A lightning arrester comprising a plurality of plates of high resistance material disposed in contact with each other, said 25 bodies being maintained at atmospheric temperature during a discharge.
13. A lightning arrester comprising a plurality of bodies of high resistance material disposed in contact with each other at a relatively small number of points and being 30 separated by short gaps at the remainder of the contact surfaces, said bodies being maintained at relatively low temperature during a discharge.
- 35 14. A lightning arrester comprising a plurality of bodies of high resistance material disposed in contact with each other at a relatively small number of points and being separated by small gaps at the remainder of 40 the contact surfaces, said bodies being maintained at atmospheric temperature during a discharge.
15. A lightning arrester comprising a plurality of bodies of high resistance material 45 disposed in contact with each other, the size and specific resistance of said bodies being such that when a discharge passes therethrough, the current density is kept sufficiently low to prevent the formation of an 50 arc.
16. A lightning arrester comprising a plurality of bodies of high resistance material disposed in contact with each other, the size and specific resistance of said bodies 55 being such that when a discharge passes therethrough, the current density is a relatively few amperes per square centimeter.
17. A lightning arrester comprising a plurality of stacked bodies of high resistance material disposed in contact with each other in a gaseous medium at a pressure on 60 the order of atmospheric pressure.
18. A lightning arrester comprising a plurality of stacked bodies of high resistance material disposed in contact with each other, the contact surfaces of said bodies being substantially plane.
19. A lightning arrester comprising a plurality of stacked disks of high resistance material disposed in contact with each other.
20. A lightning arrester comprising a plurality of stacked disks of high resistance material disposed in contact with each other, the contact surfaces of said disks being substantially plane.
21. A lightning arrester comprising a plurality of bodies of high resistance material disposed in contact with each other, the specific resistance of said material being of the order of 100 ohms per centimeter cube.
22. A lightning arrester comprising a plurality of bodies of high resistance material disposed in contact with each other, the specific resistance of said material being sufficient to prevent the formation of an arc between said bodies under a discharge.
23. A lightning arrester comprising a plurality of bodies of high resistance material disposed in contact with each other, the specific resistance of said material being such that the counter electromotive force developed in a discharge is not less than the voltage necessary to initiate the discharge between said bodies.
24. A lightning arrester comprising a plurality of bodies of high resistance material disposed in contact with each other, the specific resistance of said material being such that the counter electromotive force developed per gap in a discharge is not less than 250 volts.
25. A lightning arrester comprising a plurality of bodies of high resistance material disposed in contact with each other, the specific resistance of said material being such that the counter electromotive force necessary to maintain the discharge between said bodies is of the same order as that necessary to initiate the discharge.
26. A lightning arrester comprising a plurality of bodies of material having a discharge gap therebetween, the specific resistance thereof being sufficiently great to cause a discharge to be distributed over the discharge surfaces of said bodies, portions of said surfaces being separated a distance such that the breakdown voltage is less than 500 volts per gap.
27. A lightning arrester comprising a plurality of bodies of material, the length of the gap therebetween being sufficiently small to cause a discharge to be distributed over the surfaces of said bodies.
28. A lightning arrester comprising a plurality of bodies of material, the specific resistance thereof being sufficiently great to cause a discharge to take the glow form.

29. A lightning arrester comprising a plurality of bodies of resistance material, the length of the gap therebetween being sufficiently small to cause a discharge to take the glow form. 5
30. A series of gaps, means for causing said gaps to break down at a voltage approximately equal to the voltage necessary to maintain a discharge. 10
- 10 31. A series of gaps, the number being such that the value of the voltage at which discharge begins divided by the number of gaps is equal to a few hundred volts. 15
32. The combination with a circuit to be protected, of an excess-voltage discharge device comprising electrodes having a glow discharge therebetween at gaseous pressures substantially atmospheric. 16
- 20 33. A lightning arrester consisting of a series of discharge members, successive members of which being at some points spaced apart a distance substantially equal to that having the minimum sparking potential. 25
- 25 34. A lightning arrester comprising a plurality of plates of material, the specific resistance thereof being over 20 ohms per centimeter cube. 30
- 30 35. A lightning arrester comprising a plurality of plates of material, the specific resistance thereof being over 20 but under 150 ohms per centimeter cube. 35
- 35 36. A lightning arrester comprising a plurality of bodies of material, the spacing therebetween being, at one point at least, such that the breakdown voltage thereof is substantially equal to the voltage drop in the cathode dark space of a glow discharge. 40
- 40 37. A lightning arrester comprising a plurality of bodies of material in air, the spacing therebetween being, at one point at least, such that the breakdown voltage thereof is substantially equal to the voltage drop in the cathode dark space of a glow discharge in air. 45
- 45 38. A lightning arrester comprising a plurality of bodies of material, the spacing therebetween being, at one point at least, such that the breakdown voltage thereof is substantially equal to the voltage drop in the cathode dark space of a glow discharge in a gaseous medium at a pressure of the order of atmospheric pressure. 50
- 55 39. A lightning arrester comprising a plurality of bodies of material in a gaseous medium at substantially atmospheric pressure, the maximum spacing between effective surfaces thereof being approximately equal to the combined length of the cathode dark space, cathode glow and Faraday dark space of a glow discharge. 60
- 60 40. A lightning arrester comprising a plurality of bodies of material in a gaseous medium at substantially atmospheric pressure, the specific resistance thereof being sufficiently great and the length of gap therebe- 65
- tween being sufficiently small to cause a glow discharge having substantially no positive column to be distributed over the surfaces of said bodies. 70
41. A lightning arrester comprising a plurality of bodies of material in a gaseous medium at substantially atmospheric pressure, the specific resistance thereof being sufficiently great and the length of gap therebetween being sufficiently small to cause a discharge to take the glow form having a breakdown voltage of approximately 350 volts. 75
42. A lightning arrester comprising a pair of bodies in a gaseous medium at substantially atmospheric pressure, the specific resistance of at least one of said bodies being of the order of 100 ohms per centimeter cube. 80
43. A resistor comprising a plurality of plates of high-resistance material, said resistor being capable of allowing a relatively heavy current to pass therethrough at a predetermined voltage and preventing any substantial amount of current from passing therethrough below said voltage. 85
44. A device including an electrical element and a resistor comprising plates of high-resistance material in shunt thereto, said resistor being capable of allowing a relatively heavy current to pass therethrough at a predetermined voltage and preventing any substantial amount of current from passing therethrough below said voltage. 90
45. A space-current discharge device comprising at least one pair of electrode plates having a discharge gap therebetween, the average spacing being between $\frac{1}{3}$ and 8 mils, whereby the space-current flow between the plates always takes the form of a glow-discharge at gaseous pressure of the order of atmospheric pressure. 95
46. A space-current discharge device comprising a pair of electrode plates having juxtaposed surfaces, the major portions of said surfaces being spaced distances between the length of the cathode dark space of a glow discharge and the combined lengths of the cathode dark space, cathode glow and Faraday dark space of a glow discharge. 100
47. A space-current discharge device comprising a pair of electrode plates having juxtaposed surfaces, the major portions of said surfaces being spaced distances between the length of the cathode dark space of a glow discharge and the combined lengths of the cathode dark space, cathode glow and Faraday dark space of a glow discharge, at least one portion of the juxtaposed surfaces being spaced a distance corresponding to the minimum breakdown voltage. 105
48. A space-current discharge device comprising a pair of electrode plates having juxtaposed surfaces, at least one portion 110
- 115
- 120
- 125
- 130

- of the juxtaposed surfaces being spaced a distance corresponding to the minimum breakdown voltage, the plates being in a gaseous medium at substantially atmospheric pressure.
49. A space-current discharge device comprising a pair of electrode plates having juxtaposed surfaces, the major portions of said surfaces being spaced distances between the length of the cathode dark space of a glow discharge and the combined lengths of the cathode dark space, cathode glow and Faraday dark space of a glow discharge, the resistivity of at least one of the electrode plates being such as to insure against the concentration of the discharge into an arc under normal conditions of discharge, the plates being in a gaseous medium at substantially atmospheric pressure.
50. A space-current discharge device comprising a pair of electrode plates having juxtaposed surfaces, the major portions of said surfaces being spaced distances between the length of the cathode dark space of a glow discharge and the combined lengths of the cathode dark space, cathode glow and Faraday dark space of a glow discharge, at least one portion of the juxtaposed surfaces being spaced a distance corresponding to the minimum breakdown voltage, the resistivity of at least one of the electrode plates being such as to insure against the concentration of the discharge into an arc under normal conditions of discharge, the plates being in a gaseous medium at substantially atmospheric pressure.
51. A space-current discharge device comprising a pair of electrode plates having juxtaposed surfaces, at least one portion of the juxtaposed surfaces being spaced a distance corresponding to the minimum breakdown voltage, the plates being in a gaseous medium at substantially atmospheric pressure, the resistivity of at least one of the electrode plates being such as to insure against the concentration of the discharge into an arc under normal conditions of discharge, the plates being in a gaseous medium at substantially atmospheric pressure.
52. A space-current discharge device comprising a pair of electrode plates having juxtaposed surfaces, the spacing between said juxtaposed surfaces being such that the breakdown voltage is less than 500 volts, the resistivity of at least one of the electrode plates being such as to insure against the concentration of the discharge into an arc under normal conditions of discharge, the plates being in a gaseous medium at substantially atmospheric pressure.

In testimony whereof, I have hereunto subscribed my name this 10th day of February, 1922.

JOSEPH SLEPIAN.
